UNITED STATES PATENT OFFICE.

ADOLPH PETZOLD, OF PHILADELPHIA, PENNSYLVANIA, ASSIGNOR TO JOHN H. BROMLEY AND EDWARD BROMLEY, OF SAME PLACE, (COPARTNERS, TRADING AS JOHN BROMLEY & SONS.)

DESIGN FOR A RUG.

SPECIFICATION forming part of Design No. 34,876, dated July 30, 1901.

Application filed June 18, 1901. Serial No. 65,070. Term of patent 3½ years.

To all whom it may concern:

Be it known that I, ADOLPH PETZOLD, a citizen of the United States, residing at the city of Philadelphia, State of Pennsylvania, have invented and produced a certain new and original Design for Rugs, of which the following is a full, clear, and exact description, reference being had to the accompanying drawing, forming a part of this specification.

My design is applicable to and intended for the surface ornamentation of woven rugs. In its essentials it consists, as shown in the drawing, of an outer rectangular border *a* of small S-shaped figures, an inner border *b*, 15 composed of two parallel lines with a series

of small block figures, and a field center composed of a series of lineally-arranged small figures *c*, and alternately and intermediate of them another series of other lineally-arranged scroll-figures *d*. 20

I claim—

The design for a rug, substantially as shown and described.

In testimony whereof I have hereunto affixed my signature this 4th day of June, A. D. 25 1901.

ADOLPH PETZOLD.
